UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

ELASTIC-FLUID TURBINE.

SPECIFICATION forming part of Letters Patent No. 768,604, dated August 30, 1904.

Application filed April 29, 1903. Serial No. 154,887. (No model.)

To all whom it may concern:

Be it known that I, OSCAR JUNGGREN, a citizen of the United States, residing at Schenectady, county of Schenectady, State of New York, have invented certain new and useful Improvements in Elastic-Fluid Turbines, of which the following is a specification.

Elastic-fluid turbines of the jet type are provided with rows of wheel-buckets, between which are one or more rows of intermediate buckets which receive the motive fluid from one row of wheel-buckets, change its direction, and discharge it against a second row of wheel-buckets at the proper angle.

My invention relates to the intermediate buckets and their supports, and has for its object to improve and simplify their construction.

For a consideration of what I believe to be novel and my invention attention is called to the accompanying description and claims appended thereto.

In the accompanying drawings, which illustrate one embodiment of my invention, Figure 1 is an end elevation of a turbine with the casing broken away to show the wheel. Fig. 2 is a partial side elevation. Fig. 3 is a detail view in elevation of the intermediate buckets and their support. Fig. 4 is a plan view of the intermediates and their support separated from the turbine, and Fig. 5 is a detail view of an intermediate support of a slightly-modified construction.

Referring to Fig. 1, 1 represents the casing or shell, which may be divided into parts in any suitable manner. Mounted within the casing on the shaft 2 is a wheel (shown in the opening in the casing) having buckets of any suitable character. 3 represents a sectionalized nozzle for delivering motive fluid to the wheel, and 4 the bowls which open directly into the nozzle-passages. In order to change the direction of the fluid-stream and discharge it at the proper angle to the rows of wheel-buckets, intermediate buckets are provided which are mounted on a support 5, that extends through an opening in the casing and is adjustably supported with respect thereto.

Referring more particularly to Figs. 2 to

4, 1 represents the casing having an opening 6 formed in the lower half to receive the intermediate buckets and their support. In so far as the present invention is concerned, however, the intermediates can be mounted wherever it is the most desirable. At some suitable point on the casing is formed a projection 7, with which the adjusting-screws for the upper end of the intermediates engage. The intermediate buckets 8 are formed integral with their base 9 and may be cast or cut by suitable means out of solid stock. The left-hand side of the base is curved on an arc struck from the wheel-axis, and the outer or right-hand ends of the buckets are similarly formed. The bucket-support 10 is provided with an inner face that is turned true and is concentric with the outer ends of the buckets which engage therewith. The outer end of the support has a flange 11, that acts as an attaching means and also as a cover for the opening 6. At points adjacent to the bucket-supporting surfaces are openings 12, and located therein are nuts for the clamping-bolts 13, which pass through the buckets and their base into the support. The size of the openings can be varied to suit the conditions; but it will be found desirable to make them large enough to receive the hand, so that the nuts can be readily mounted in place. The heads of the bolts are countersunk, so that the inner curved surface of the bucket-base will present an unbroken surface to the wheel. The flange 11 of the support is provided with lugs 14 at its upper end, that are located on opposite sides of the projection 7, and each is provided with an adjusting-screw 15. At the lower end and on opposite sides are lugs 16, each of which carries an adjusting-screw 17, that engages the side of the casing 1. In order to clamp the intermediates in place, a number of bolts 18 are employed which have a certain amount of clearness around their bodies, so that when they are backed off slightly the buckets can be adjusted in a plane parallel with the wheel-axis. Formed on the casing below the end of the flange 11 is a guide 19 for directing the axial movements of the buckets during adjustment.

Thus far mention has been made of a single row of buckets only; but where there are more than two rows of wheel-buckets it becomes necessary to provide an additional row 5 or rows of intermediates. Referring to Fig. 4, it will readily be seen how two or more rows of buckets can be supported. The support 10 is provided with as many curved projections 20 as there are rows of buckets, and 10 the space 21 between the rows is when the parts are assembled occupied by the wheel-buckets. The present structure being intended for three wheels per stage, there would be in addition 15 a row of wheel-buckets outside of the intermediates. The projections are curved concentrically with respect to the wheel-axis and are beveled slightly from the receiving to the discharge side of the buckets. In the present illustration the lower projection has the 20 smaller bore and is the one nearer the sectionalized nozzle. The object of this bevel is to enlarge the spaces or passages between buckets to compensate for the increased volume of motive fluid due to decreased pressure.

25 In Fig. 5 is shown a slightly-different form of intermediate, where one large opening 12 is provided with overhanging ends for the support. The retaining-bolts 13 pass through the bucket structures into the support as before.

30 The flange 5 is arranged to be attached to the casing, and two or more segmental rows of intermediates may be used.

In accordance with the provisions of the patent statutes I have described the principle 35 of operation of my invention, together with the apparatus which I now consider to represent the best embodiment thereof; but I desire to have it understood that the apparatus shown is only illustrative and that the invention 40 can be carried out in other ways.

What I claim as new, and desire to secure by Letters Patent of the United States, is—

1. In an elastic-fluid turbine, the combination of a wheel-casing, a shaft, a bucket-support 45 attached to the casing and provided with one or more openings, intermediate buckets formed integral with their base at one end and engaging with said support at the other, and retaining devices which pass through the 50 bucket structure and enter the opening or openings in the support.

2. In a turbine, the combination of a wheel- 55 casing, an intermediate bucket-support hav-

ing a plurality of projections formed thereon and one or more openings in each for receiving 55 retaining devices, a row of buckets for each projection, each row formed integral with its base and extending outwardly therefrom, and retaining devices which pass through the base of the buckets into the 60 opening or openings formed in the supports.

3. In a turbine, the combination of a wheel-casing, an intermediate bucket-support having 65 a plurality of projections formed thereon, and one or more openings for receiving retaining devices, a means for attaching the support to the casing, a row of buckets for each projection, each row being formed integral with its base and extending outwardly therefrom, and retaining devices which pass 70 through the base of the buckets into the opening or openings formed in the supports.

4. In a turbine, the combination of a wheel-casing having an opening formed therein, an intermediate bucket-support having a flange 75 which closes the opening in the casing, a plurality of curved projections on the support, intermediate buckets formed integral with their base and engaging at their outer ends with the curved surfaces of the projections, 80 and bolts for attaching the buckets to their support.

5. In an elastic-fluid turbine, the combination of a casing, a curved bucket-support having 85 one or more openings formed therein, buckets formed integral with their base and engaging at their unconnected ends with the curved surface on the support, a plurality of bolts passing through the bucket structure 90 into the opening or openings in the support, and means for adjustably securing the bucket-support to the casing.

6. In an elastic-fluid turbine, the combination of a casing having an opening formed 95 therein, a support projecting through said opening and provided with a flange that engages the casing, buckets that are detachably secured to the support, lugs attached to the casing and the flange, and adjusting means carried by the lugs.

In witness whereof I have hereunto set my hand this 28th day of April, 1903.

OSCAR JUNG(GREN).
